UNITED STATES PATENT OFFICE.

HENRY B. TURNER, OF WASHINGTON COURT-HOUSE, OHIO.

ROTARY ENGINE.

SPECIFICATION forming part of Letters Patent No. 761,341, dated May 31, 1904.

Application filed February 4, 1904. Serial No. 191,959. (No model.)

To all whom it may concern:

Be it known that I, HENRY B. TURNER, a citizen of the United States of America, and a resident of Washington Court-House, county of Fayette, State of Ohio, have invented certain new and useful Improvements in Rotary Engines, of which the following is a full and clear specification, reference being had to the accompanying drawings, in which—

10 Figure 1 is a vertical sectional view taken centrally through the engine; Fig. 2, a vertical sectional view taken at right angles to the line on which Fig. 1 is taken; Fig. 3, a horizontal sectional view taken centrally 15 through the engine, and Fig. 4 a vertical transverse section taken on the line 4-4 on Fig. 3.

The object of this invention is to provide a simple and efficient engine of the rotary type 20 which shall require but few packings to keep its various moving parts steam-tight, as more fully hereinafter set forth.

Referring to the drawings by reference characters, the letter *a* designates the casing 25 or cylinder, which is in the form of a ring and is provided with a continuous ring-like bore. This casing or cylinder is constructed of two halves bolted together at their outer edges by bolts *b*. The piston *c* is circular in shape, so as 30 to fit the bore of the cylinder, and is constructed in any suitable manner and projects radially from a disk *d*, to which it is rigidly attached in any suitable manner. The disk *d* is keyed to the power-shaft *e* and fits and works be- 35 tween the inner edges of the casing-halves, suitable annular packages *f* being set in the adjacent faces of the casing-halves in order to prevent leakage of steam at these points. The shaft *e* may be supported by brackets 40 bolted to the engine-casing or in any other suitable manner.

At each side of the casing is formed a horizontally-disposed gate-box *g*, in which is mounted on a vertical pivot *h* a rotary disk 45 or gate *i*, which extends across the cylinder-bore and forms an abutment or head. Each of these gates is provided at its edge with a circular opening which is adapted to register with the bore of the cylinder and to permit

the piston to pass therethrough at certain intervals. These disks are operated automatically in any suitable manner. The means I show consist of a cam *j*, fixed to the power-shaft and adapted to actuate the rods *k*, which at their inner ends are provided with anti-friction-rollers which bear upon the face of the cam at diametrically opposite points. Each rod *k* is provided with a small piston *l*, which works in a small cylinder *m*, mounted on the main cylinder and supplied with steam through a pipe *n*. The outer end of each rod *k*, which works through the closed outer end of cylinder *m*, is pivotally connected to the link *o*, which in turn is pivotally connected to a lever *p*, which lever is pivotally mounted in 65 the casing *g* and has its free end connected to the disk or gate by a pin-and-slot connection.

Above and below each gate in the casing are mounted valves *q* and *r*, the latter being 70 inlet-valves and the former being exhaust-valves and the ports leading from these valves being so arranged as to enter the cylinder adjacent to the gates.

In operation it will be observed that the 75 steam forces the piston to travel around the continuous cylinder, the gates or valves serving as heads or abutments. For instance, when the piston passes down through the opening in the right-hand gate said gate immediately closes and steam is admitted under the same by means of the inlet-valve *r*. At the same instant the exhaust-valve *q* at the opposite side is caused to open, so that as the piston *c* moves around the steam in the compartment immediately ahead of it will pass out through said valve *q*. Then as piston *c* moves toward the left-hand gate or abutment the same will be caused to gradually open, thereby letting a portion of the exhaust-steam 85 into the upper half of the cylinder and permit it to pass out through the other exhaust-valve at the opposite side of the engine. When piston *c* passes through the left-hand gate, said gate immediately closes and the inlet-valve *r* 90 is opened, and as the piston travels toward the right-hand valve *q* the exhaust-steam ahead of it will be forced out through said

valve until the right-hand gate begins to open, whereupon a portion of the exhaust will pass into the lower part of the cylinder and out through the left-hand exhaust-valve, and so on. It will be observed that the gates or abutments are opened gradually and closed suddenly. This gradual opening is accomplished by the rods and levers shown, and the sudden closing is obtained by the small steam-cylinders *m*, suitable means being provided to admit steam behind the small piston *l* at the instant that the rollers on the rod *k* drop off the shoulder of the cam.

Any suitable mechanism may be employed 15 to operate the valves *q* and *r*. For instance, an eccentric may be keyed on the engine-shaft and connected to a rocker-arm attached to the main cylinder, which in turn drives a wrist-plate that oscillates on the cylinder through 20 which the engine-shaft passes, the stems of the valve being connected to the wrist-plates by means of rods which are adjustable.

It will be observed that the engine takes steam twice in each revolution of the shaft, 25 and it is obvious that any suitable automatic cut-off may be used, so as to permit the steam to work expansively.

It will be observed that this engine can be used for a great variety of purposes and may 30 be set to run at any angle and in practically any position and also that it has a maximum of power, is very simple in all its parts, easy to repair, and has no dead-center. It will also be observed that it may be made to run from 35 one revolution to an indefinite number of revolutions per minute and that it will be inexpensive to build.

It will be obvious from the foregoing that 40 my invention is not confined to the specific features of construction shown and described, and that, therefore, I reserve the right to vary the construction shown and described with-

out departing from the spirit of my invention.

Having thus described my invention, what 45 I claim as new, and desire to secure by Letters Patent, is—

1. In combination with a ring-like cylinder, oscillating gates mounted therein and extending across the bore of said cylinder at different points, means for slowly opening said gates, and steam-actuated means for quickly closing said gates, and inlet and exhaust valves adjacent to the gates, of a concentric power-shaft carrying a disk working through 50 the inner wall of said ring-like cylinder and carrying a piston working in said bore.

2. In a rotary engine the combination, of a ring-like cylinder, oscillating gates mounted therein and extending across the bore of the 60 said cylinder at different points, mechanically-operated means for slowly opening said gates, steam-actuated means for quickly closing said gates, a power-shaft carrying a disk working through the inner wall of said ring-like cylinder 65 and carrying a piston working in said bore.

3. In a rotary engine the combination, of a ring-like cylinder, oscillating gates mounted therein, levers connected to said gates, cam-actuated devices for moving said levers to open the gates, steam-actuated means to actuate 70 said lever to close said gates, inlet and exhaust valves adjacent to the gates, a power-shaft carrying a disk working through the inner 75 wall of said cylinder and carrying a piston working in said bore.

In testimony whereof I hereunto affix my signature, in the presence of two witnesses, this 2d day of February, 1904.

HENRY B. TURNER.
